UNITED STATES PATENT OFFICE.

CHARLES FREDRICK BECK, OF NEWARK, NEW JERSEY, ASSIGNOR, BY MESNE ASSIGNMENTS, TO ELIAS CLEIN, OF NEW YORK, N. Y.

COMB.

Application filed January 19, 1920. Serial No. 352,450.

To all whom it may concern:

Be it known that I, CHARLES FREDRICK BECK, a citizen of the United States, residing at Newark, county of Essex, State of New Jersey, have invented certain new and useful Improvements in Combs, of which the following is a specification.

My invention relates to an improvement in combs, and more particularly to the handle of combs.

The type of comb to which my invention is particularly applicable is a relatively heavy metal comb which is used to take the curl or kink out of hair. In using the comb to accomplish the indicated purpose the teeth of the comb are passed through the hair substantially parallel to the scalp to straighten the hair initially and then the teeth are turned outwardly in a direction away from the scalp and the back or body of the comb is used to press or further smooth the hair to retain it in straightened condition. In this operation considerable strain is applied to the handle, which in the constructions at present generally employed comprises a shaft inserted in the comb body and a wire helix encircling the shaft. It was found in practice that with this construction there was not sufficient rigidity between the handle and the body of the comb to permit the latter to operate efficiently, particularly during that part of the combing operation when the back of the comb is pressed against and moved along the head. Frequently the comb turned relatively to the handle, this seriously detracting from the effectiveness of the device.

With the foregoing in mind, the principal object of my invention is to provide an improved construction of comb in which the handle is rigid with the body and the wire helix which surrounds the handle is firmly anchored to prevent turning thereof.

The invention is illustratively exemplified in the accompanying drawing, wherein Fig. 1 is a side elevational view of the comb, and Fig. 2 a fragment of the comb with parts shown in section.

In the drawing, 10 denotes the back or body of the comb provided with the teeth 11. The comb is, as above stated, preferably

made of metal and is relatively wide at the body portion 10 tapering towards the teeth 11. One end of the comb body is provided with the substantially cylindrical stub extension 12 from which projects the integral shaft 13 having the head or knob at its outer end.

Encircling the shaft 13 is a wire helix 15, forming the handle proper, and having its lower end formed as a ring 16 and its upper end relatively tightly coiled and laid in circumferential grooves 17 in the stub extension 12, these grooves extending spirally about such extension.

It will be noted that the helix is of greatest diameter at its middle part to afford an adequate hand hold, while its lower end abuts and is braced by the knob 16 and its upper end is tightly coiled about the extension 12 in the grooves thereof. As a result of this construction there is no danger of the comb turning in or relatively to the helix 15 no matter how strongly the comb be pressed against the head.

I claim:

1. A comb comprising a body portion having a circumferentially grooved extension, a shaft formed integrally with and smaller in diameter than said extension, and a helix surrounding said shaft and having the coils at one end thereof laid in the grooves of said extension.

2. A comb comprising a body portion having an integral cylindrical extension provided with spiral circumferential grooves, a shaft integral with and smaller in diameter than said extension and having an enlargement at the end thereof opposite said extension, and a helix surrounding said shaft and having one of its ends braced against said enlargement and the coils at its other end laid in the grooves in said extension, one of said coils engaging the end of the extension adjacent the shaft.

In testimony whereof I have affixed my signature in presence of two witnesses.

CHAS. FREDRICK BECK.

Witnesses:

HYMAN CLEIN,
MICHAEL KANE.
